UNITED STATES PATENT OFFICE.

CHARLES TURNER, OF CHICAGO, ILLINOIS.

PROCESS FOR EXTRACTING OILS FROM SOLIDS.

1,104,456.

Specification of Letters Patent.

Patented July 21, 1914.

Application filed June 26, 1911. Serial No. 635,503.

To all whom it may concern:

Be it known that I, CHARLES TURNER, a citizen of the United States, and resident of Chicago, county of Cook, and State of Illinois, have invented certain new and useful Improvements in Processes for Extracting Oils from Solids, of which the following is a specification, and which are illustrated in the accompanying drawings, forming a part thereof.

The invention relates to improvements in the method of extracting oils from solids and has especial reference to means for preventing the loss of the solvent agent when it assumes the form of vapor.

The method may be practised by means of various forms of apparatus. There is shown in the accompanying drawings a sectional view of an apparatus suitable for this purpose.

The device shown in the drawings comprises a plurality of cylinders designated respectively by the numerals 12, 30 and 42. These cylinders are set at an incline. The solid material is received at the lower end of each and is discharged from the upper end thereof. The cylinder 12 is provided with a receiving hopper 10 discharging into the cylinder at 11. A tubular shaft 16 is suitably journaled upon the axis of the cylinder and upon this shaft there is mounted a spiral conveyer 16 which carries the material through the cylinder and discharges it therefrom through a down-spout 29 into the lower and receiving end of the cylinder 30. The major portion of the cylinder 12 is inclosed within a jacket 13 and the inclosed portion of the cylinder wall is foraminous as indicated at 14. A solvent material such as gasoline is delivered to the cylinder through the shaft 16 which is freely perforated as shown at 19, the solvent being delivered to the bore of the shaft through a pipe 17 which is connected to the cylinder through the stuffing box 18. The cylinder 30 and its appurtenances are substantially identical with the cylinder 12 and its appurtenances, there being present an inclosing jacket 34, the walls of the cylinder inclosed by the jacket being foraminous as shown at 35; there being present a tubular shaft 32 freely perforated as shown at 33, a spiral conveyer 31 mounted upon the shaft, and a pipe 36 for delivering the solvent to the upper end of the shaft. The material is carried through

the cylinder and discharged therefrom through the down-spout 41 delivering to the lower end of the third cylinder 42 which with its appurtenances is substantially identical in construction with the other cylinders so far as described, there being present an inclosing jacket 43, a tubular shaft 45 having a stuffing box 46 at its end, and being freely perforated as shown at 47; a spiral conveyer 44 mounted upon the shaft and the walls of the cylinder being foraminous as shown at 92.

The pipe 17 leads from the delivery side of a pump 72, the suction side of which is connected by means of a pipe 73 with a tank 93 containing the solvent material. A pipe 20 leads from the jacket 13 at or above the level of the throat 11 of the hopper 10, discharging to a receiving tank 21. The pipe 20 is provided with a controlling valve 22. Drain pipes 23, 24 lead from the jacket 13 at lower levels than the connection therewith of the pipe 20 and each is provided with a controlling valve 25, 26. A valve-controlled pipe 28 leads from the lower end of the cylinder 12. The pipes 23, 24, and 28 all deliver to the tank 21. In the normal action of the apparatus the solvent delivered into the material through the shaft perforations 19 escapes into the jacket 13 through the perforations in the cylinder 12, carrying with it much of the oils with which the material is charged. These liquids accumulate within the casing 13 to the level of the pipe 20, the valve of which is normally open; the valves of the pipes 23, 24 and 28 being closed. This accumulation of liquid within the jacket 13 and the lower end of the cylinder 12 forms a liquid seal for preventing vapors from escaping through the hopper.

Within the tank 21 the oils will tend to be separated to some extent from the solvent by gravity and are carried off through an overflow pipe 74 to an evaporator 75, where so much of the solvent material as may be carried off with the oils in vapors passes off through the pipe 76 to a condensing coil 56, from which it is discharged through the pipe 77 to a receiving tank 78. The oils escape from the evaporator 75 through the pipe 79 to a suitable separator 80.

Solvent material is delivered to the cylinder 30 from the tank 78 by means of a pump 81 connected with this tank by a pipe 82. This solvent being delivered into the ma-

terial as it passes through the cylinder 30 completes the washing, the liquids draining into the casing 34 and accumulating therein to the level of the bottom of the lower end of the down-spout 29, and thus forming the liquid seal for preventing the escape of any vapor back through the down-spout 29.

10 The pipes 37, 38, 39 and 40 connect the jacket 34 and cylinder 30 with a receiving tank 93, which delivers to the reservoir 75 through an overflow pipe 83.

15 Within the cylinder 42 the material is heated for the purpose of receiving any of the solvent material which may have been carried with it from the cylinder 30. For this purpose steam or other heating fluid is delivered into the cylinder through the shaft 45 and the vapors escape into the jacket 43, from which they are discharged through 20 nipples 52, 53 and 54 into a header 51 and being conveyed thence through a pipe 55 to the condensing coil 56. A steam trap 85 is placed in the pipe 77 for eliminating the water of condensation.

25 Pipes 48 and 49 lead from the lower ends respectively of the jacket 43 and cylinder 42 to the tank 50 for the purpose of carrying off any liquids which may be drained from the material.

30 In order to prevent the vapors from escaping from the cylinder 42 backwardly through the down-spout 41 or forwardly through the delivery-spout 57 through which the material is finally discharged from the apparatus, steam jets are introduced into the spouts 41 and 57 and are directed in each case toward the chamber of the cylinder 42. This is accomplished in the apparatus shown in the drawings by providing hollow belts 58

40 and 61 for encircling respectively the spouts 41 and 57. An annular series of small discharge openings 60 and 63 leading through the walls of the pipes 41 and 57 form the chambers of these belts, in the one case being 45 directed downwardly and in the other case being directed upwardly. Pipes 59 and 62 are shown as entering the chambers of the hollow belts. The jets of steam or other heated fluid which may thus be discharged

50 into the chamber of the cylinder 42 constitute seals for preventing the escape of vapors from the cylinder.

The apparatus is shown as being mounted in part upon a floor 89 and part upon an upper floor 90 of a building. Power is applied to the several shafts from a belt pulley 64 mounted upon the shaft 65 and which is provided with pinions 66, 67 and 68 meshing with gear wheels 69, 70 and 71 fixed upon 60 the several shafts. Safety vents 86, 87 lead from the upper ends of the cylinders 12 and 30.

65 The apparatus as described forms the subject of a pending application for patent Serial No. 631,440 filed June 5, 1911, made by

this applicant jointly with Harry J. Flood but the process may be carried out by various other means such as the apparatus forming the subject of the joint application Serial No. 633,126 filed June 14, 1911 of the said 70 Turner and Flood. The essential features of the invention forming the subject of this application are the liquid seals for preventing the escape of vapors backwardly from the chambers within which the dissolving or 75 washing operation is performed and the vapor seal for preventing the escape of vapors from the last or drying chamber.

I claim as my invention—

1. The herein described process of extracting oils from solids, consisting in passing the solid material through an upwardly inclined chamber, washing the material with a volatile solvent within the chamber, maintaining the liquid drained from the material within the chamber at a suitable level to seal the receiving end of the chamber, draining the liquids laterally from the material within the chamber into a separating tank, and discharging the material from the chamber 90 through a liquid seal. 80

2. The herein described process of extracting oils from solids consisting in passing the solid material through a chamber, washing the material with a volatile solvent within 95 such chamber, discharging the material from the chamber through a liquid seal, then passing the material through a second chamber, washing it therein with a volatile solvent, discharging the material from such chamber 100 into and passing it through a third chamber, applying heat to the material while in such third chamber for vaporizing the solvent remaining in the material, discharging the material from such chamber, and introducing into the material as it enters and leaves such chamber a vapor under pressure in the form of jets directed toward the chamber in both cases. 105

3. The herein described process of treating solid material for extracting oils therefrom consisting in first washing the material with a volatile solvent, then passing the material through a chamber and heating it therein for vaporizing the solvent remaining in the material, and sealing the receiving and discharge ports of such chamber against the escape of vapors therethrough by directing into such chamber through such ports a vapor under pressure. 110

4. The herein described process of treating solid material for extracting oils therefrom consisting in first washing the material with a volatile solvent, then passing the material through a chamber and heating it therein for vaporizing the solvent remaining in the material, and sealing the port of such chamber against the escape of vapors therethrough by directing into such chamber through such port a vapor under pressure. 115 120 125 130

5. The herein described process of extracting oils from solids, consisting in delivering the material to the lower end of an inclined chamber through a liquid seal, conveying
5 the material through the chamber, delivering a volatile solvent to the center of the mass of material as it passes through the chamber, draining the liquid from the mass

laterally and discharging it to a separating tank and discharging the material from the chamber through a liquid seal.
